Letters Patent No. 1141. Dated Augt. 30. 1859.

The schedule referred to in these Letters Patent and making part of the same.

To all whom it may concern:

Be it known that I, Henry Graham Thompson, of the City, County and State of New York, have invented or produced a new and original design for a pattern to be wrought into True Ply Ingrain and other carpeting, in colors similar to those painted on the drawings accompanying this Specification, or in others to be substituted in the place of those painted on the drawings herewith. And I do hereby declare that the drawings accompanying this Specification do give and convey to any one skilled in the art of carpet making a more defined and thorough description of the nature of my invention than it is in the power of language otherwise to do, and is sufficient to enable any one skilled in the art of carpet making to use my invention.

What I claim as my invention and desire to secure by Letters Patent, is the configuration of the design herunto annexed when made by being wrought into True Ply Ingrain or other Carpeting, in the form similar to the drawings accompanying this Specification.
